DESIGN FOR AN ADVERTISING SIGN

Julius G. Berens, Brooklyn, N. Y.

Application February 8, 1939, Serial No. 82,863

Term of patent 3½ years

To all whom it may concern:

Be it known that I, Julius G. Berens, a citizen of the United States, residing at Brooklyn, in the county of Kings and State of New York, have invented a new, original, and ornamental Design for an Advertising Sign, of which the following is a specification, reference being had to the accompanying drawing, forming part thereof,

Figure 1 is a front elevational view of an advertising sign, showing my new design.

Figure 2 is an end edge elevational view of the same.

I claim:

The ornamental design for an advertising sign, as shown,

JULIUS G. BERENS.
